(57) **CLAIM**

The ornamental design for vessel for storing liquids and powders, as shown and described.

DESCRIPTION

FIG. 1 is a top, front, right side perspective view of a claimed design;

FIG. 2 is a bottom, front perspective view thereof;

FIG. 3 is a top plan view thereof;

FIG. 4 is a bottom plan view thereof;

FIG. 5 is a front elevation view thereof;

FIG. 6 is a left side elevation view thereof;

FIG. 7 is a right side elevation view thereof;

FIG. 8 is a rear elevation view thereof; and,

FIG. 9 is a cross-section view taken along the line 9-9 in the FIG. 5 drawing view.
